CLAIM

The ornamental design for a LED light lens, as shown and described.

DESCRIPTION

FIG. 1 is a top front perspective view of a LED light lens; FIG. 2 is a top plan view of FIG. 1;

FIG. 3 is a bottom plan elevation view of FIG. 1;

FIG. 4 is a front elevation view of FIG. 1, the rear elevation view being a mirror image thereof;

FIG. 5 is a right side elevation view of FIG. 1, the left side elevation view being a mirror image thereof; and, FIG. 6 is a detail section view of FIG. 1, taken along line 6-6 of FIG. 5.

The broken lines shown in the drawings depict portions of the LED light lens that form no part of the claimed design.
